BACKREST FOR A BICYCLE SEAT

George W. Worley, Bolivar, Tenn., assignor to Troxel Manufacturing Company, Moscow, Tenn., a corporation of Ohio

Filed May 29, 1968, Ser. No. 12,135

Term of patent 14 years

Int. Cl. D12—14

U.S. Cl. D90—16

FIG. 1

FIG. 2

FIG. 3

FIG. 4

FIG. 1 is a front elevational view of a backrest for a bicycle seat, showing my new design.

FIG. 2 is a back elevational view thereof.

FIG. 3 is a side elevational view thereof as viewed from one side. The side opposite that shown in FIG. 3 is a mirror image thereof.

FIG. 4 is a sectional view taken as on the line IV—IV of FIG. 1.

The seat support shown fragmentarily and in broken lines is included for illustrative purposes only.

I claim:

The ornamental design for a backrest for a bicycle seat, as shown and described.
